UNITED STATES PATENT OFFICE.

ROBERT OLIN PICKENS, OF SPARTANBURG, SOUTH CAROLINA.

SLASHER-HOOD.

1,326,420.

Specification of Letters Patent. Patented Dec. 30, 1919.

Application filed May 31, 1919. Serial No. 301,110.

To all whom it may concern:

Be it known that I, ROBERT OLIN PICKENS, a citizen of the United States of America, and a resident of Spartanburg, county of 5 Spartanburg, and State of South Carolina, have invented certain new and useful Improvements in Slasher-Hoods, of which the following is a full and clear specification.

The object of this invention is to provide 10 a hood arranged in such manner with respect to the cylinders and size-box of the slasher that the rising vapors will be collected and carried away so that they will not condense and fall or drip back upon the 15 yarn and spoil the same, as more fully hereinafter set forth.

In the drawing—

Figure 1 is a side elevation, partly broken away, showing my apparatus applied to a 20 well-known type of slasher;

Fig. 2 is a vertical sectional view taken through the line 2—2 of Fig. 1;

Figs. 3 and 4 are detail sectional views hereinafter described.

Fig. 5 is a view showing the connections 25 of the pipes to a main.

My improved hood is arranged to extend entirely over the two cylinders as well as the size-box of the apparatus. It is desirably suspended at each end by a suitable 30 cable *a* or other means, and it consists of a top-wall *b* and two depending side-walls *c*. The top-wall and side-walls curve up over the main cylinder, so as to completely hood 35 the upper side thereof. The top-wall is made in sections and is bolted to angle-irons *d* so that the sections may be removed from time to time, when rusted or otherwise worn out, and replaced by new sections.

The interior of the hood is divided into 40 two compartments by a baffle-wall *e* extending across the hood about on a line with the back-edge of the size-box, thereby forming a smaller compartment at the forward end 45 of the hood, directly over the size-box. Along the lower edge of the baffle-plate *e* is formed a condensation trough *f* which receives the water of condensation formed in the compartment over the size-box and delivers it to a suitable discharge-pipe *g* at one 50 end of the trough. This special condensation chamber and drainage trough are arranged directly over the size-box because it is at that point where the greatest film of 55 steam or vapor arises.

The vapor not condensed in the condensa-

tion compartment above the size-box is drawn off through a transverse slot *h* formed in the top-wall thereof, this slot being connected to a funnel-shaped dome *i* provided 60 at its apex with an annular flange *j* which is adapted to be connected to an exhaust pipe (not shown). A similar conical dome *i* is formed at the uppermost point at the other end of the hood, *i. e.*, at a point directly over the center of the main cylinder. These conical dome-shaped exits *i* are to be connected to a tube from which the air is drawn by means of a blower, so that the vapors arising into the hood will be constantly drawn off from the interior thereof. 70

Instead of the ceiling hangers *a*, or in addition thereto, I may support and brace the hood by suitable rods *l* connecting the respective ends of the hood to the frames of the 75 slasher apparatus. I prefer also to provide in each depending wall, at a point over the small cylinder, an outwardly-opening door *m* to enable inspection of the interior to be had. The exhaust openings *j* 80 may be connected up in any suitable manner with a system of exhaust pipes; I prefer to connect these exhaust openings by means of pipes *n* to a main *o* to which the exhaust blower is connected. In practice, these 85 slashers are arranged in rows, and this main *o* serves as a common conduit for the exhaust products of an entire double row of machines, it being desirable to increase the diameter of the main *o* as it approaches the 90 fan to take care of the increased quantity of exhaust products from the various slashers.

The condensation compartment over the kettle is desirably provided with a depending flap-door *p* at each side and a similar 95 door *p* at the end, which serves to inclose the area above the kettle and thus make the steam rise better into the compartment above. These flaps are arranged to readily swing outwardly and upwardly to permit 100 inspection and manipulation of the devices in the kettle. In addition to these depending flaps *p*, I may provide the transverse partition *e* with a depending extension *q* secured by a slot and thumb-nuts to the partition walls *e*, so as to have vertical adjustment on said wall; this depending plate *q* serves to still further house the top of the kettle and to direct the steam up into the condensation compartment. Desirably, the 105 condensation drainage-trough *f* is formed on the lower edge of this depending wall *q*,

although, as shown in Fig. 2, this trough may be formed integral with the lower edge of the wall *e*.

The nature and scope of the invention having been thus indicated and its preferred embodiment having been specifically described, what is claimed as new is:

1. A hood adapted to be supported over the cylinders and size-box of a slasher and having openings for removing the vapors from the interior of the hood, said hood being provided with a baffle-plate at a point near the size-box to form a condensation compartment directly over the size-box, a drainage-trough being provided for said condensation compartment.

2. A hood adapted to be supported over the cylinders and size-box and having openings for removing the vapors from the interior of the hood, said hood being provided with a baffle-plate at a point near the size-box to form a condensation compartment directly over the size-box, a drainage-trough being provided for said condensation compartment.

partment, and flap-doors depending from the condensation compartment being provided to house or inclose the space between the size-box and the hood.

3. A hood adapted to be supported over the cylinders and size-box and having openings for removing the vapors from the interior of the hood, said hood being provided with a baffle-plate at a point near the size-box to form a condensation compartment directly over the size-box, a drainage-trough being provided for said condensation compartment, the transverse inner wall of said condensation compartment being provided with a vertically-adjustable extension depending to a point below the bottom edge of the hood.

In testimony whereof I hereunto affix my signature.

ROBERT OLIN PICKENS.
